FIG. 1

UNITED STATES PATENT AND TRADEMARK OFFICE
CERTIFICATE OF CORRECTION

PATENT NO. : Des. 518,941 S
APPLICATION NO. : 29/200994
DATED : April 18, 2006
INVENTOR(S) : Allen et al.

It is certified that error appears in the above-identified patent and that said Letters Patent is hereby corrected as shown below:

Title Page

On the face page, in field (75), in "Inventors", in column 1, lines 2-3, delete "Brooklyn Park," and insert --Plymouth, --, therefor.

On the Title page, in field (73), in "Assignee", in column 1, line 1, delete "MInneapolis," and insert -- Minneapolis, --, therefor.

On the Title page, in field (57), under "Claim", in column 2, line 1, delete "bar," and insert -- bar --, therefor.

On Title page 2, in field (56), under "Other Publications", in column 2, line 5, delete "Kelloggs's," and insert -- Kellogg's, --, therefor.

On Title page 2, in field (56), under "Other Publications", in column 2, line 22, delete "Grancom" and insert -- Granco, --, therefor.

On title page 2, in field (56), under "Other Publications", in column 2, line 26, delete "Marshallow" and insert -- Marshmallow --, therefor.

Signed and Sealed this

First Day of August, 2006

JON W. DUDAS
Director of the United States Patent and Trademark Office
